CLAIM

The ornamental design for a jewelry display stand, as shown and described.

DESCRIPTION

In referring to the drawings, FIG. 1 is a rear perspective view of a jewelry display stand showing my new design;

FIG. 2 is a top plan view thereof;

FIG. 3 is a front elevational view thereof;

FIG. 4 is a right side elevational view thereof, the left side being a mirror image thereof;

FIG. 5 is a bottom plan view thereof;

FIG. 6 is a rear and left side perspective view of a second embodiment of the display stand of FIG. 1;

FIG. 7 is a top plan view thereof;

FIG. 8 is a front and right side elevational view thereof;

FIG. 9 is a right side elevational view, the left side being a mirror image thereof;

FIG. 10 is a bottom plan view thereof;

FIG. 11 is a front perspective view of a third embodiment of the display stand of FIG. 1;

FIG. 12 is a top plan view thereof;

FIG. 13 is a front elevational view thereof;

FIG. 14 is a rear elevational view thereof, and;

FIG. 15 is a bottom plan view thereof.
